His Attorney.

UNITED STATES PATENT OFFICE

2,136,226

PARTITION ASSEMBLY FOR FREEZING TRAYS

Leonard W. Atchison, Schenectady, N. Y., assignor to General Electric Company, a corporation of New York

Application December 1, 1936, Serial No. 113,694

4 Claims. (Cl. 62—108.5)

My invention relates to freezing trays for refrigerating machines, and more particularly to partition assemblies for such trays provided with a heating arrangement for readily freeing the ice cubes therefrom.

In the use of prior metal freezing trays, it has been customary to remove ice cubes or the like by allowing warm water to run over the trays and partition assembly carrying the ice cubes until the latter is freed from the tray. Warm water is then allowed to run over the partition assembly and ice cubes until the latter are loosened from the partition assembly and fall therefrom. The ice cubes are then collected in a suitable pan such as a freezing tray, for use as desired. This method is wasteful due to the melting of the ice from the cubes, and somewhat inconvenient. Furthermore, difficulty has been experienced in removing frozen desserts and the like due to the fact that it is objectionable for water to come into contact with them.

Accordingly, it is an object of my invention to provide an improved partition assembly for a freezing tray which is adapted to receive a heating element which renders it possible to loosen ice cubes or the like from the freezing tray and partition assembly in an easy manner without the use of water.

Another object of my invention is to provide an improved partition assembly for a freezing tray which is capable of being directly removed from the freezing tray without disturbing the ice cubes therein, thus permitting the freezing tray to serve as a collecting pan for the ice cubes and making it unnecessary to handle the ice cubes.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawing in which Fig. 1 is a perspective view of a freezing tray containing a partition assembly embodying my invention and a removable heating element therefor; and Fig. 2 is a perspective view of one of the partition elements employed in constructing the partition assembly shown in

Fig. 1.

Referring to the drawing, in Fig. 1 I have shown a shallow rectangular metal freezing tray 10 containing a partition assembly 11. Preferably, the partition assembly 11 comprises a plu-

rality of similarly formed partition elements 12 of substantially Z-shape arranged in series and spot welded or otherwise secured together at the adjacent surfaces thereof, as disclosed and claimed in my Patent No. 2,077,200, granted April 13, 1937, and assigned to the General Electric Company, the assignee of my present invention.

Each of the similarly formed partition elements 12 of substantially Z-shape is preferably made of aluminum or other material of good thermal conductivity and is provided with a longitudinal extending central portion 13 and oppositely extending transverse portions 14 and 15 at each end, respectively, of the longitudinal extending portion. The partition elements 12 are assembled in series relationship with the central portions 13 thereof in substantially axial alignment along the center of the partition assembly, a part of the central portion of each partition element overlapping a part of the central portion of the next succeeding partition element in the assembly. These overlapping parts of the central portions 13 of the partition elements are rigidly secured together, preferably, by the fusion of metal, that is, by spot welding, soldering or the like, thus forming joints of good thermal conductivity therebetween. The transverse portions 14 and 15 of the partition elements 12 are disposed in spaced parallel relationship with respect to each other, thus dividing the tray 10 into a series of individual compartments in which blocks of ice or the like may be frozen.

An L-shape end partition element 16 is rigidly secured to one end of the partition assembly described above. The end partition element 16 includes a longitudinal extending portion 17 and a transverse extending portion 18. The end partition element 16 is preferably secured to the adjacent Z-shape partition element 12 by the fusion of metal as, for example, by spot welding a part of the longitudinal portion 17 of the end partition element 16 adjacent the edge thereof to the abutting part of the longitudinal portion 13 of the partition element 12. A second end partition element 19 is secured to the opposite end of the partition assembly in the same manner as that described with respect to the end partition element 16.

Each of the similarly formed partition elements 12 and end partition elements 16 and 19, constituting the partition assembly 11 above described, are provided with an arrangement for removably receiving a heating element. As will be seen in Fig. 2, this arrangement comprises two projections or tabs 20 and 21 formed in

tegral with the central portion 13 of each partition element 12 and upstanding therefrom. These upstanding tabs are bent in opposite directions into substantially half-round configuration to slidably receive and resiliently grip the heating element, so as to obtain good thermal contact. The longitudinal extending portions of the end partition elements 16 and 19 are provided with upstanding tabs similar to tabs 20 and 21 provided the longitudinal extending portion 13 of each of the partition elements 12.

When the partition assembly 11 is constructed as above described, the tabs 20 and 21 formed on each of the partition elements slidably receive the heating element 22 in good heat exchange relationship therewith. The heating element 22 comprises an elongated tubular portion 23 provided with an electric heating element therein, a heat insulated handle 24, and suitable electric conductors in a cable 25 connecting the heating element to a source of supply.

The partition elements which constitute the partition assembly above described are preferably made of a metal having a good thermal conductivity, such as aluminum, so that heat generated in the heating element 22 may readily flow therefrom through the tabs 20 and 21 provided the individual partition elements 12 into the body of the partition assembly 11 to thaw the bond between the ice cubes contained therein and the partition assembly. In removing ice cubes or the like from the freezing tray 10, the freezing tray containing the partition assembly 11 and the ice cubes therein is removed from the refrigerated compartment of a refrigerating machine, and the elongated tubular portion 23 of the electric heating element 22 is inserted into the tabs arranged throughout the length of the partition assembly 11. Heat generated in the elongated tubular portion 23 of the electric heating element 22 passes through the upstanding tabs 20 and 21 into the longitudinal extending portions 13 and then into the transverse extending portions 14 and 15 of the partition elements 12. Likewise, heat passes through the upstanding tabs provided the partition elements 16 and 19 into the longitudinal and transverse extending portions thereof. After a short interval of time sufficient heat will pass through the heating element 22 into the partition assembly 11 and the freezing tray to completely thaw the bond between the ice cubes, freezing tray, and the partition assembly. The partition assembly as a whole then may be removed from the freezing tray 10 by lifting the same vertically with the handle 24 provided the electric heating element 22, leaving the ice cubes in the freezing tray 10. Thus, the freezing tray 10 serves as a collecting pan for the ice cubes.

It will thus be seen that I have provided an improved partition assembly for a freezing tray which includes an arrangement for removably receiving a heating element, thus permitting easy

removal of ice cubes or the like from the freezing tray and obviating the necessity of handling the ice cubes while they are being removed.

While I have shown a particular embodiment of my invention in connection with a rigid metallic freezing tray, I do not desire my invention to be limited to the particular construction shown and described and I intend in the appended claims to cover all modifications within the spirit and scope of my invention.

What I claim as new and desire to secure by Letters Patent of the United States is:

1. In combination with a freezing tray, a removable partition assembly comprising a plurality of metallic partition elements, each of said partition elements being provided with means comprising two tabs bent in opposite directions for receiving a removable heating element.

2. In combination with a freezing tray, a removable partition assembly comprising a plurality of metallic partition elements, each of said partition elements being provided with means comprising a tab for receiving a removable heating element, said partition elements being arranged in series with a tab on adjacent partition elements being bent in opposite directions to receive said heating element.

3. In combination with a freezing tray, a removable partition assembly comprising a plurality of substantially Z-shaped metallic partition elements, each of said partition elements being provided with means for receiving a removable heating element, said partition elements being arranged in series with said receiving means arranged to slidably receive said heating element, a part of the surface of the central portion of each of said partition elements overlapping a part of the surface of the central portion of another of said partition elements in abutting relationship therewith, said abutting surfaces being secured together, the legs of said partition elements being arranged in spaced parallel relationship to define the walls of a freezing tray compartment.

4. In combination with a freezing tray, a removable partition assembly comprising a plurality of metallic partition elements, each of said partition elements having a longitudinally extending portion, oppositely extending transverse portions at each end of said longitudinal extending portion, and at least two tabs upstanding from said longitudinally extending portion bent in opposite directions into a substantially half-round configuration to receive an elongated heating element, said partition elements being arranged in series and rigidly secured together with a part of the surface of said longitudinal portion of each of said partition elements in abutting relationship with said part of the surface of the longitudinal portion of another of said partition elements.

LEONARD W. ATCHISON.
